W. D. DAVIS

HYDRO-AUTO-HELICOPTER

Filed June 14, 1924

FIG. 3

FIG. 2

Witness

G. Lowell Edgeworth

FIG. 1

Inventor

William Daniel Davis

UNITED STATES PATENT OFFICE.

WILLIAM DANIEL DAVIS, OF LITTLE ROCK, ARKANSAS.

HYDRO-AUTO-HELICOPTER.

Application filed June 14, 1924. Serial No. 720,068.

To all whom it may concern:

Be it known that I, WILLIAM DANIEL DAVIS, a citizen of the United States, residing at Little Rock, in the county of Pulaski and State of Arkansas, have invented a new and useful Hydro-Auto-Helicopter, of which the following is a specification.

My invention relates to improvements in combination hydro-auto-helicopter, in which a plurality of vacuum propellers are attached to a body vertical or otherwise, rigid or adjustable; (in this case adjustable) said body provided with two or more folding wings or planes on each side, that may be turned vertically or horizontally, or folded back against side of vessel; a folding tail and rudder that may be folded up on top of vessel; and four wheels supporting vessel when on the ground by means of side beams with springs and air pump shock absorbers; and the objects of my improvements are, first, to provide a body that can be propelled on the water, land or in the air; second, to provide said body with a plurality of vacuum propellers attached to the body vertically or otherwise to propel the machine on water, land or in the air, vertically, forward, backward or in a circle; two or more folding wings on each side; and folding tail and rudder with controls; and four wheels with steering gear in front for operating said machine; and third, to reduce the danger in rising and landing perpendicularly, by use of the vacuum propeller, the adjustable wings, the adjustable tail and rudder and spring beam axle support.

I attain these objects by the mechanism illustrated in the accompanying drawing, in which—

Fig. 1, is a side elevation of the entire machine; Fig. 2, a detailed section of one form of propeller; Fig. 3, a vertical section showing the wing and spiral propeller construction.

Similar numerals refer to similar parts throughout the several views.

The body 1, and cab top, with sloping boat bottom 3, and bar at outer edge of propellers attached to body and cab by brace arms constitute the frame work of the machine.

A plurality of vacuum propellers 2, attached to body 1, at bottom, with swivel 17, where crank shaft 19 enters cylinder 14, with top attached to control stick 7, by means of a shifting bar, cable and pulley,

so top of propeller may stand perpendicular or be moved forward or backward as desired; said vacuum propellers consisting of a cylinder 14, said cylinder equipped with spiral propeller blade 20, which is driven by pulley and belt connected to an engine.

Fig. 3, shows cylinder 14, equipped with spiral propeller blade 20, which is driven by bevel gearing 21, and connected to an engine; an adjustable wing is attached to the plane; the propeller shown in Fig. 3, is mounted on the body the same as the propeller shown in Fig. 2; a headlight 13, in front and fuel tank 12 is arranged at back; and at the side two or more folding planes 4, attached to arm by wrist joint 5, so that planes may be turned perpendicularly or horizontally, or folded back against side of vessel as shown by dotted lines in Fig. 1; a folding tail and rudder 6, can be folded up on top of body 1, as shown in Fig. 1; four wheels with steering gear in front are mounted on axles; said axles being connected to support beams 8, at their lower ends, the beams being attached to the body; and provided with spring 9, and shock absorber 10, at top end; a pontoon at bottom of cylinders on each side shown by dotted lines; a side shield 23, and door 25, shown by dotted lines; a flange 24, between cylinders at wing line may be added. One adjustable spiral blade propeller is attached horizontally to front end of fuselage, and one to back end, driven by pulley and belt connected to an engine, for turning machine to right or left or parking sidewise.

I am aware that prior to my invention, hydro-auto-air ships have been made to run on water, land or in the air. I therefore do not claim such a combination broadly; but

I claim:

A combination hydro-auto-helicopter, comprising a body, with cab and sloping boat bottom; a plurality of vacuum propellers adjustably attached to the body; said vacuum propellers comprising a cylinder; said cylinder provided with a spiral propeller blade which is connected by means of bevel gearing to be driven by an engine; said propeller cylinders connected below to the body by a swivel where the drive shaft enters the cylinder; a bar at the top of the cylinder connected to a control stick, so top of propeller may stand perpendicular, or be

15 moved forward or backward; two or more beam axle support at lower end; said beam adjustable wings on each side of the body mounted by a joint and arm adjustable; to stand perpendicular when ascending or horizontal when flying forward, or be folded back against the side of vessel when running on land or water or for housing; a folding tail and rudder with hinge on top and latch below, so as to fold up on top of body when used on water or land or for housing; four wheels under the body connected with steering gear; said wheels mounted on axles, said axles attached to side

15 moved forward or backward; two or more beam axle support at lower end; said beam connected to the body, and provided with 15 springs and air pump shock absorbers above; a pontoon on each side below the cylinders; a side shield with door, and a flange between the cylinders that closes the space automatically when descending perpendicular; one adjustable spiral blade propeller attached to front end of fuselage and one to back end, driven by pulley and belt connected to an engine, for turning machine to right or left or parking same sidewise.
